UNITED STATES PATENT OFFICE.

AUGUST H. PFUND, OF BALTIMORE, MARYLAND.

VACUUM-PRODUCING METHOD AND MEANS.

1,146,019.

Specification of Letters Patent. Patented July 13, 1915.

Application filed February 26, 1914. Serial No. 821,233.

To all whom it may concern:

Be it known that I, AUGUST H. PFUND, a citizen of the United States, and a resident of Baltimore, in the State of Maryland, have **5** invented a new and useful Improvement in Vacuum-Producing Methods and Means, of which the following is a specification.

My invention relates to vacuum producing methods and apparatus and particularly to methods of and means for restoring **10** impaired vacuum in chambers or receptacles or for accentuating or increasing such vacuum as may be produced by means of pumps.

15 The object of my invention is to provide a simple, inexpensive and effective method and means that shall be available and ready for use, whenever needed, to remove such gases as may impair the vacuum in a chamber, either immediately after disconnection from a pump or at any time during service.

My invention may be utilized effectively and advantageously in connection with any apparatus having a chamber or chambers in **25** which it is necessary or desirable to maintain a high degree of vacuum but it will be found especially useful in connection with vapor lamps and rectifiers and other apparatus embodying electrical conductors and **30** electrodes to be operated in a highly developed vacuum.

An example of apparatus to which my invention may be advantageously applied is shown in the accompanying drawing, the **35** single figure of which is a diagrammatic view of a mercury vapor rectifier and its circuits having my vacuum restoring or accentuating apparatus attached thereto.

The drawing illustrates the bulb or container **40** 1 of a mercury vapor rectifier which may be formed of either glass or metal and be provided with electrodes for connection to supply and work circuits in the usual manner.

45 Further description of the rectifier and its circuit connections is unnecessary, both because such apparatus is well known in the art and because the rectifier is shown merely as an example of vacuum apparatus in general and without restrictive intent. Attached to the bulb or container 1 is an auxiliary bulb or container 2 of glass or metal having an electrode 3, preferably, but not necessarily, of iron in its upper end, and an **50** electrode 4, consisting of a body of gas-absorbing material, in its bottom. I have

found that comminuted charcoal, such, for example, as cocoanut charcoal, is a satisfactory gas-absorbing material but other materials, such, for example, as platinum black **60** may be employed, if desired. The auxiliary container also has in it, near electrode 3, a small piece of platinum or other suitable wire 8 having terminals brought to the outside and in electrical connection with electrode 3. The electrode 8 may be heated to incandescence by a battery of dry cells or other convenient source 9. The electrode 8 is hereinafter called the Wehnelt electrode. **65**

The terminals 3 and 4 are connected to the **70** secondary winding 5 of a transformer 6, the primary winding 7 of which may be supplied from any suitable source. If my apparatus is used with a vapor rectifier, the primary winding 7 may be supplied from the **75** source to which the rectifier is connected. The ratio of transformation will be such that the secondary winding shall provide from 1000 to 6000 volts, according to the size and characteristics of the apparatus as a whole. **80**

In order to start the discharges between the electrodes 3 and 4 under certain conditions, I may utilize the Wehnelt electrode 8 by heating it to incandescence by means of **85** current from the source 9, or from any other suitable source.

In order to prevent the passage of charcoal dust from the auxiliary chamber 2 to the main chamber 1 and the passage of mercury particles from the chamber 1 to the **90** chamber 2, the connecting tube 10 may be provided with an enlargement 11 in which is placed a body of glass wool or other suitable material that is sufficiently porous to serve as an effective screen. **95**

In using my apparatus, a suitable vacuum pump is connected to the main chamber 1 at any desired suitable point and is operated, while a heavy electrical discharge is maintained between the electrodes 3 and 4 **100** until the occluded gases are expelled from the charcoal. Then the discharge is stopped and the tube is highly exhausted. The pump may then be sealed off from the chamber 1 by sealing off the connection, and the apparatus be allowed to cool until the charcoal is at substantially room temperature. Gas which leaks into the chamber 1 or is given off by electrodes or other solid bodies contained within the chamber may **105** then be partially absorbed by the charcoal if a high-potential discharge is produced **110**

by means of the transformer 6, the discharge being effected without the use of the Wehnelt electrode 8 but gradually becoming very feeble. In order to complete the 5 evacuation, a vigorous discharge may be started by heating the Wehnelt electrode 8 and such discharge may be continued until the last traces of gas are removed from the chamber 1. The auxiliary case 2 and its 10 electrodes will constitute a permanent attachment for the case 1 but the transformer 6 and the battery 9 may be used in connection with any desired number of vacuum chambers.

15 The outfit described may be used repeatedly, and will serve to insure a satisfactory working vacuum in the apparatus with which it is used during a long period of service. In case the gas-absorbing qualities 20 of the material 4 become impaired, they may be restored by connecting the entire apparatus to an air pump, driving out the gases absorbed by the charcoal by means of a heavy, high-potential discharge and then 25 exhausting the entire apparatus to the limit of the pump before sealing off.

It will be understood that my invention is not limited to definite materials, forms or dimensions except as the same may be 30 specified in the appended claims.

I claim as my invention:

1. The method of restoring or accentuating the vacuum in a vacuum chamber that consists in producing high-potential alternating current discharges between a metal electrode and a body of gas-absorbing material in an adjacent communicating chamber.
2. The method of restoring or accentuating the vacuum in a vacuum chamber that consists in producing high-potential electrical discharges between a metal electrode and a body of gas-absorbing material in a communicating chamber.
3. The method of restoring or accentuating the vacuum in a vacuum chamber that consists in producing high-potential electrical discharges between two electrodes, one of which is a body of gas-absorbing material and both of which are in an auxiliary chamber having a constricted connection to said vacuum chamber.
4. The combination with a vacuum chamber and an auxiliary chamber having a limited communication therewith having electrodes in its respective ends one of which

is a body of gas-absorbing material, of means for producing high-potential electrical discharges between said electrodes.

5. The combination with a vacuum chamber and a connecting auxiliary chamber having opposing electrodes one of which is a body of gas-absorbing material, of means for producing high-potential discharges between said electrodes and means for initiating such discharges. 60

6. A vacuum chamber having means for restoring or accentuating its vacuum comprising an auxiliary chamber having opposing electrodes one of which is a body of gas-absorbing material, and a source of high-potential electrical energy connected to said electrodes. 70

7. A vacuum restoring or accentuating apparatus comprising a vacuum chamber having opposed electrodes one of which is a body of gas-absorbing charcoal, and means for producing high-potential discharges between said electrodes. 75

8. A vacuum restoring or accentuating apparatus comprising a vacuum chamber having opposed electrodes one of which is a body of gas-absorbing material, means for producing high-potential discharges between said electrodes, and means for breaking down the resistance to such discharges. 80

9. A vacuum chamber provided with means for accentuating or restoring its vacuum comprising an auxiliary chamber having coöperating electrodes one of which is a body of gas-absorbing material, means for producing high-potential discharges between said electrodes, a constricted conduit between said chambers and a screen in said conduit. 90

10. The combination with a main vacuum chamber, of an auxiliary chamber connected to said main chamber by a relatively small conduit, a screen of porous material in said conduit, opposed electrodes in said auxiliary chamber one of which is a body of gas-absorbing material, and means for producing high-potential discharges between said electrodes. 100

In testimony whereof, I have hereunto 105 subscribed my name this twenty-first day of February 1914.

AUGUST H. PFUND.
